UNITED STATES PATENT OFFICE

MOSES E. CHENEY, OF TOLEDO, OHIO, ASSIGNOR TO MOTO METER GAUGE & EQUIPMENT CORPORATION, OF TOLEDO, OHIO, A CORPORATION OF DELAWARE

AUTOMOBILE HORN

Application filed January 16, 1931. Serial No. 509,243.

The main object of my invention is to provide an improved construction of enclosure for automobile horns, such that an emblem-carrying cover piece may be readily replaceable without the use of tools, but which piece when in place will be held in such a substantial manner that it will not be shaken out by the vibration of the horn or by shocks given to the automobile on the road.

10 In the accompanying drawings,

Figure 1 is a face view of the front of the horn;

Fig. 2 is a section through the outer margin of the front cover, but with the replaceable emblem-carrying centre piece in side view;

Fig. 3 is an enlarged sectional view through the top of the joint between the marginal part of the cover and the replaceable centre piece;

Fig. 4 is a corresponding view of the bottom part of the joint;

Fig. 5 is a view on the line 5—5 of Fig. 4.

In these drawings I have illustrated my invention as applied to an automobile signalling horn of the type illustrated in the Cheron Design Patent No. 79,499, dated Oct. 1st, 1929. The characteristic appearance of this type of horn is that of an enlarged watch case, comprising a back supporting piece A, Fig. 2, and a front cover B, the two being dished to receive between them the electromagnetic signalling means.

According to my present invention I make the front piece in two parts, an outer marginal part B' which is fixedly united at its margin with the back piece A, and a removable centre piece C.

This removable centre piece C may be made or provided with suitable ornamentation, as for example, the trademark of the manufacturer of the horn or of the maker of the automobile, or the monogram of the owner of the car or the emblem of the club or association to which the owner of the car belongs, or any other desired indication.

As a rule, the maker of the horn will be apt to send the horn out on the market with a removable centre piece bearing his name or trademark or the like, but the dealer or

the producer of the horn may readily remove this centre piece and replace it by another bearing some other name, or monogram or other indication, as desired. Dealers may be supplied with various types and styles of these centre pieces or medallions for just such replacements. For example in a given locality, it may be convenient to have a stock of medallions indicating that locality or indicating membership in a club or association of that locality.

In order that these centre pieces or medallions may be readily removable and replaceable without the use of tools, I form the margin of each centre piece or medallion C with a re-curved flange D at the back, which curved flange is cut at intervals Figs. 2 to 5, so as to produce a continuous series of bent spring tongues d—d, around the periphery of the centre piece.

The re-curving of the flange D of the medallion is such with relation to the opening in the marginal part B' of the cover that when the medallion is pressed up to the said marginal part of the cover, the spring fingers d—d will snap past the inner edge of the marginal part B' as indicated in Figs. 2 and 3, while a folded rim C' formed on the medallion back of the flange D will lie against the outer face of the part B'.

In order that the correct position of the medallion may be insured, I provide a projecting tongue b, at one point on the inner edge of the marginal piece B', to enter a corresponding slot d' in the flange D of the centre piece, as illustrated in Figs. 4 and 5.

With the described construction, the centre pieces can be readily replaced, but owing particularly to the substantially continuous ring of curved spring fingers, centre pieces once inserted will not rattle or be knocked out of place by any ordinary hard usage.

I claim:

1. An automobile horn, provided with a front cover having a marginal part and a removable centre piece with a series of curved spring fingers at its edge to fit into the marginal part and retain the center piece in position, and a tongue and slot connection to locate the position of the centre piece.

2. An automobile horn, provided with a front cover having a marginal part and a removable centre piece with a series of curved spring fingers to fit into the marginal part and retain the center piece in position and a folded rim back of the fingers and continuous therewith to bear against the outer face of the marginal part.

5 In testimony whereof I have signed my
10 name to this specification.

MOSES E. CHENEY.
